PEEP SIGHT FOR FIREARMS

George E. Hennessy, Libby, Mont.

Application February 25, 1937, Serial No. 127,750

3 Claims. (Cl. 33—58)

This invention relates to peep sights for fire arms and more particularly to a construction which may be quickly adjusted for different ranges, and it consists in the constructions, arrangements, and combinations herein described and claimed.

It is an object of the invention to provide a sight which may be readily used as a peep sight, adjustable upon its base support so as to be adaptable to various ranges, as well as being susceptible to use as a receiver sight.

It is a further object of the invention to provide a peep or similar sight which may be quickly folded to an inoperative position.

15 It is a still further object of the invention to provide a sight which is longitudinally adjustable along its supporting base, the base having graduations cooperable with the sight to indicate the range.

20 It is also an object of the invention to provide a sight which may be quickly adjusted vertically.

Additional objects, advantages and features of invention will be apparent from the following description and accompanying drawing, wherein

25 Figure 1 is a side elevation of the sight.

Figure 2 is a front elevation thereof.

Figure 3 is a vertical sectional view through the sight.

Figure 4 is a side elevation of the sight in inoperative position and illustrating the graduations to insure adjustment of the sight to a desired range of fire.

Figure 5 is an enlarged perspective view of a lock bolt employed in the sight.

35 There is illustrated a portion of a gun 10 upon which there is mounted my sight 11. The sight comprises a base 12 having a curvature as at 13 to fit the gun barrel or breech, as the case may be, and bolts 14 may be employed to secure the sights to the gun. A pair of spaced parallel upstanding flanges 15 are formed as an integral part of the base 12, and these flanges preferably are inclined rearwardly. Each of the flanges 15

40 has formed therein a slot 16 extending longitudinally of the flanges and parallel to the upper edge thereof. It will be noted that the slots are inclined with respect to the bore of the gun.

45 A peep sight mounting lug 17 is provided, having a base member 18 of a width freely receivable between the flanges 15 and includes a threaded stem 19 cooperable with an internally threaded bore 20 of a sight 21. A lock nut 22 is also engaged upon the stem 19 abutting the lower end of

55 the sight 21. It will be apparent that the sight

21 may be adjusted upon the threaded stem 19 and secured in such position by the lock nut 22.

The lug 17 has an aperture 23 adapted to align with the slots 16 of the flanges and a bolt 24 is extended through the slots and the aperture 5 23. The bolt 24 has a head 25 of flattened formation so as to seat within one of the flanges 16 and thus prevent its turning when tightening the nut 26 which is engaged upon the threaded portion of the bolt. The bolt 24 has a flat 27 for a 10 purpose as will now be explained.

The lug 17 has a bore 28 extending longitudinally thereof and houses a helical spring 29 and a detent 30. The spring urges the detent outwardly so as to contact the bolt 24 and in the 15 vertical position of the lug 17 the detent 30 will seat upon the flat 27 of the bolt and thus retain the sight in proper erect position. It will be understood, of course, that the lug 17 may be oscillated upon the bolt so as to move the sight to 20 an inoperative position as shown in Figure 4. In such movement, the spring 29 permits rearward movement of the detent 30 so as to become released from the flat 27.

One of the slots 16 will have calibrations indicated at 31 and the bolt head 25 will have an index 32.

In use, the nut 26 will be slightly loosened so as to release binding action of the flanges 15 upon the lug 17, thus permitting the lug 17 and associated sight 21 to be moved along the slot 16 to a desired point as indicated by the calibrations. Movement of the sight 21 forwardly will by reason of the upward inclination of the slot cause elevation of the sight and backward movement of 35 the sight will lower the sight and the range of fire will be accordingly changed.

While I have shown and described a preferred embodiment of the invention this is by way of illustration only, and I consider as my own all 40 such modifications in construction as fairly fall within the scope of the appended claims.

I claim:—

1. In a sight for fire arms, a base member having parallel upstanding flanges thereon, each flange having a slot inclined with respect to the gun bore, a bolt disposed across the slots, and movable longitudinally thereof, said bolt having a flattened head engaged within one of the slots, a lug positioned between the flanges and oscillatably mounted on the bolt, detent means on the lug cooperable with the bolt to maintain the lug in a desired position and a vertically adjustable sight on the lug.

2. In a sight for fire arms, a base member hav-

55

ing parallel upstanding flanges thereon, each flange having a slot inclined with respect to the gun bore, a bolt positioned across the slots and movable longitudinally thereof, said bolt having a flattened head at one end disposed within one of the slots, the other end of the bolt having a screw threaded nut thereon, a lug positioned between the flanges and oscillatably mounted on the bolt, said lug having a bore extending transverse to the bolt, a detent in the bore, a helical spring positioned between the detent and the closed end of the bore, said bolt having a flattened portion de-

fining a seat in one position of movement of the lug, said lug having a screw threaded shank, a peep sight threadedly engaged on the shank, and a lock nut on the shank cooperable with the sight for locking the same in a desired position.

3. In a sight for firearms, a base member having parallel upstanding flanges, each flange having a slot inclined with respect to the gun bore, a bolt having its ends slidably mounted in the respective slots, and a sight member pivotally mounted on said bolt between said flanges. 5 10

GEORGE E. HENNESSY.
